UNITED STATES PATENT OFFICE.

CHARLES HARTER, OF BARBERTON, OHIO.

MECHANICAL STOKER.

989,254.

Specification of Letters Patent. Patented Apr. 11, 1911.

Application filed September 23, 1909. Serial No. 519,298.

To all whom it may concern:

Be it known that I, CHARLES HARTER, citizen of the United States, residing at Barberton, in the county of Summit and State of Ohio, have invented certain new and useful Improvements in Mechanical Stokers, of which the following is a specification.

My invention relates to mechanism for distributing fuel over the grate surface of a furnace, the object of my invention being to provide a mechanism which can be applied with equally good results to the furnaces of locomotives, steam ships, or stationary boilers.

15 A further object of my invention is to provide a stoker of simple and compact construction, which shall be economical and effective in the distribution of coal over the grate surface, which shall have a large capacity in handling coal, be simple to operate, and provide a stoker of great efficiency.

20 A still further object is to provide a mechanism by which the coal may be distributed at the will of the operator, over or 25 upon any particular zone of distribution on the grate surface.

These objects I attain by means of the construction now to be described and illustrated in the drawings, wherein:

30 Figure 1 is a plan view of my apparatus as applied to a furnace, the casing of the apparatus being shown in section; Fig. 2 is a longitudinal section of Fig. 1 on the line 2-2; Fig. 3 is an enlarged perspective 35 detail view of the mechanism for operating the fuel box and for operating the clutches to reverse or stop the driving mechanism, the casing being removed and one of the charging bars being broken away; Fig. 4 is a side 40 elevation of a part of the mechanism shown in Fig. 3; Fig. 5 is a fragmentary transverse section partly in elevation of the parts shown in Fig. 4; Figs. 6, 7, 8 and 9 are diagrammatic views showing the various positions 45 taken by the bell crank lever shown in Fig. 4; Fig. 10 is a detail elevation of the driven shafts for actuating the charging bars and the gears carried thereby, the supporting bars being in section; Fig. 11 is a transverse 50 section of the hopper, the outer casing and the supporting bar; and, Fig. 12 is a top view of the pull rod for dumping the coal carrier.

Corresponding and like parts are referred

to in the following description and indicated 55 in all the views of the drawings by the same reference characters.

In these drawings, A designates a furnace of any ordinary construction, such as used for locomotive, marine, or stationary boilers, 60 and B indicates the grate thereof, a indicating the stoking opening.

Mounted in front of the front wall of the furnace A and above the stoking opening a is a hopper 2, of a shape to be hereafter described, the lower end of the hopper being extended to form a relatively contracted discharging neck 3 closed at its lower end by a sliding door 4, the means of operating which will be hereafter described.

70 5 designates a casing or inclosure, preferably of metal, within which the operating mechanism of the stoker is carried, and which supports the hopper 2. This casing is supported within the locomotive or adjacent 75 to the furnace in any desired manner, and is open at its rear end to permit the rearward movement of the charging bars.

My stoking apparatus comprises, in general terms, two or more sets of charging 80 arms or bars, each set carrying at its end a coal carrier, preferably having the form of a pocket, and each set operable so that it may be drawn into such position as to bring the pocket mounted thereon into alignment 85 with the hopper to receive the coal, then forced into the furnace to the point required, then dumped, and then returned to position beneath the main hopper 2. I have shown, in the drawing, two sets of these 90 charging bars, each with a coal pocket, and each provided with its own actuating mechanism, which actuating mechanism is independent of the actuating mechanism for the other set. I will therefore describe one set 95 of charging bars and the actuating mechanism therefor, it being understood that both sets are alike. Referring now to Fig. 1, it will be seen that each set of charging bars comprises two opposed bars 8 held in suitable spaced relation to each other by cross bars or other means, which are adapted to be forced into the charging opening a and into the furnace, the bars being supported within the casing 5 upon a series of opposed 100 pairs of supporting rolls 6. A pair of rolls 7 also depend from the top of the casing 5 and operate upon the upper faces of the

pair of charging bars so that said bars are held in rolling contact with the rolls 6. It will be seen that the pair of opposed charging bars are supported between the rolls 6 and 7, and that they may be forced in either direction into or out of the furnace. The charging bars are made of channel iron and are provided upon either the upper or lower flanges of the channel iron with the rack teeth 10 which are shown in the drawing as located upon the upper face of the lower flange 9 of the channel bar 8. Between the forward ends of the bars is located the pocket 12 which is formed at its bottom into a plurality of compartments 14, each closed upon one side by the inclined gate or valve 15 which is pivoted at its upper end to the bottom of the pocket 12. Pivotedly connected to each of the gates 15 is a connecting rod 16 which is attached to the downwardly extending extremity 17 of a double bell crank lever. One arm of this lever has upon it the counterbalance weight 18, while the other arm of the lever is connected to a rod 20, whereby the gates 15 may be operated to permit the coal within the pocket 12 to dump onto the grate bars. The means of operating the dumping mechanism will be described in its due order.

In order to operate the charging or distributing bars 8 and to carry them into or out of the furnace, I provide the parallel shafts 30 31 mounted within bearings 32 and carrying upon their opposite ends the pinions 33 which engage with the rack teeth 10 on the arms 8. Mounted loosely upon the shafts 30 31 are the loose gear wheels 34 and 35 which mesh with each other. Engaging with the gear wheel 34 and driving it, is the gear wheel 36 mounted on the shaft 37, which shaft is driven by a belt 38 from any suitable source of power. Inasmuch as the gear wheels 34 and 35 intermesh with each other, it will be obvious that one wheel will turn reversely to the other wheel. For the purpose of connecting the loose gear wheels 34 and 35 to their respective shafts 30 and 31, I provide the clutches 40 41 which are of any suitable construction and are slidingly mounted upon the shafts 30 31 so that when shifted into place they will connect either the gear wheel 34 or 35 with its respective shaft. It will thus be seen that when the clutch 40 is in gear with the wheel 34, the shaft 30 will be driven directly from the source of power and that the pinions 33 on the shaft 30 will act to drive the bars 8 in one direction or the other, depending upon the direction of movement of the shaft 37, while when the clutch 40 is disconnected from the wheel 34, and the clutch 41 is in engagement with the wheel 35, the power will be transmitted to the loose gear 34, thence to the gear 35, thence to the shaft 31, and

thence to the pinions 33 on the shaft 31, and the shaft 31 will rotate in the opposite direction to the shaft 30.

For the purpose of throwing one of the clutches 40 or 41 into engagement with its corresponding gear wheel, and throwing the other clutch out of engagement, I provide the opposed shipper arms 44 and 45, pivoted at their lower ends in any suitable fixed base. These shipper arms are connected by links 46 to the opposed arms 47 of a bell crank lever, the middle arm 48 of which extends rearward and is connected by a link 49 to an arm 50 mounted on a rock shaft 51. It will be seen that a rotation of the rock shaft 51 in either direction (as illustrated most clearly in Fig. 3) will act to turn the bell crank lever 47, and, through the links 46, draw one of the shippers 45 in one direction and force the other shipper 44, in the opposite direction, and that thus the clutches 40 and 41 will be oppositely shifted to reversely drive the bars 8, as previously described.

It is my design to provide means for dumping the carrier pocket at certain predetermined points or positions in the furnace. In order to provide for this automatic dumping of the fuel carrying pocket at these points or positions, I provide automatic means for successively engaging the pull rod 20 at certain points in its length, as it moves into the furnace. Thus the rod 20 will be engaged, first, when it is only moved a short distance into the furnace. On the next following inward movement of the charging bars, the pull rod 20 will be engaged at a point farther along its length. Upon the next following movement, the pull rod will be engaged at a point still farther along its length or nearer to the spring end and so on, thus distributing the coal each time upon a different zone of the fire. To this end I provide the rod 20 with a plurality of teeth arranged as shown in Fig. 12, the tooth 20^a being nearest the lever 17, the tooth 20^b being next, the tooth 20^c succeeding the tooth 20^b and that in turn being succeeded by a tooth 20^d. For a reason which will be obvious later, these teeth must be out of alignment, the tooth 20^a being shown as spaced laterally from the pull rod 20, the tooth 20^b being mounted immediately adjacent to one side of the rod, the tooth 20^c being located immediately over the rod and the tooth 20^b being mounted adjacent to the side of the rod opposite to the tooth 20^b. As a means for successively engaging said teeth in their regular order and exerting a pull upon the rod 20, I mount upon the casing 5, above the bars 8 and slightly in advance of the gear wheels 34, a shaft 61. This carries upon it a plurality of disks, the disks being the same in number as the teeth on the pull rod 20 and corresponding thereto in a lateral posi-

tion. Thus in the drawing there are four pairs of teeth on the pull rod and consequently four disks, respectively numbered 60^a, 60^b, 60^c and 60^d. Each disk has projecting from it a number of teeth 62 which are adapted to engage with the corresponding pair of teeth on the pull rod 20. These disks are so arranged that the teeth thereof have a quartering relation to each other.

5 Thus in the position shown in Fig. 3 the teeth of the disk 60^a extend downward, those of the disk 60^b extend rearward, those of the disk 60^c upward and those of the disk 60^d forward or toward the furnace. Thus as 10 the shaft 61 is rotated each of the pairs of teeth in turn will be brought into a downwardly extending position, hence into position to engage the corresponding pairs of teeth on the pull rod 20. The teeth on the 15 pull rod 20 have reversely inclined upper faces, as shown in Figs. 2 and 3, and thus the teeth on the rod will successively engage with the corresponding teeth on the disks upon a forward movement of the rod toward 20 the furnace, but will slip by the teeth upon 25 a rearward movement without engaging them.

Carried upon the outer extremity of the shaft 61 is a fixed head 63 which engages 30 with a shiftable sleeve 64 whose inner face is provided with a series of ratchet teeth 65. These teeth have their inclined edges facing forwardly or toward the furnace, as shown in Fig. 3. The shaft 61 passes 35 through a bearing in the frame 5, this bearing being extended, as at 68, (Fig. 5) and surrounding this bearing is a loose sleeve 70 carrying upon it the arms 71 and 72 located at right angles to each other and forming 40 a bell crank lever. The arm 71 is connected by a link 73 to an arm 74 projecting from the rock shaft 51 previously referred to, so that when the sleeve 70 is turned, the rock shaft 51 will be turned, and through the 45 connections to the shipper arms 44 and 45, the clutches will be operated, as previously described. A spring 66 acts to force the sleeve 64 toward the sleeve 70, so that the teeth 65 on the sleeve 64 will engage with the 50 corresponding teeth on the sleeve 70. It will thus be seen that the rotation of the shaft 61 in one direction is resisted by the necessity of operating the sleeve 70, the link 73 and the rock shaft 51 with its attaching 55 connections to the clutches. It will also be noted that a rotation of the shaft 61 in one direction will cause a movement of the sleeve 70, but a reverse movement of the sleeve 70 may be secured without operating 60 the shaft.

Assuming now that the bars 8 are moving into the furnace, it will be obvious that when any one of the pairs of teeth 20^a, 20^b, 20^c, or 20^d engages with its corresponding 65 ratchet disk on the shaft 61, as the bars 8 advance, the rod 20 will be halted in its forward movement, and that therefore as the bars 8 advance a pull will be exerted upon the rod 20 which will act to turn the bell crank 17, move the rod 16 and open the 70 gates 15, allowing the coal to slide out upon the fire. It will also be obvious that the position at which this coal will be dumped into the furnace, will depend entirely upon which of the disks 60^a, 60^b, 60^c, or 60^d are 75 turned so as to bring the teeth thereon into downwardly extending position where they can engage with their corresponding teeth on the bar 20. Thus, if the parts are in the position shown in Fig. 3, the teeth on the 80 disk 60^a will be downward, and as a consequence, the teeth 20^a will be engaged upon the next forward movement of the bars 8, and thus the dumping gates 15 will be 85 opened when the bars have only advanced to their first position within the furnace or covering the zone *w*. If, however, the disk 60^b were turned with its teeth downward, then the teeth 20^b would be engaged, and the coal would be dumped upon the zone 90 *x*. The same operation would occur with the disks 60^c and 60^d, and the teeth 20^c and 20^d to dump the coal upon the zones *y* and *z*, as shown in Fig. 2.

It will be seen that by manipulating the 95 clutches as previously described, the pinions 33 will engage the bars 8 to carry the bars into the furnace, and at the proper time, to dump the coal.

The means for causing an automatic reversal of the driving gears so that the bars 8 shall be withdrawn from the furnace immediately upon the coal being dumped, are as follows: The resistance to the rotation of the shaft 61 caused by the necessity of operating the clutch shifting mechanism is sufficient to resist the initial pull of the rod 20 when its teeth become engaged by a disk. After the rod 20 has been withdrawn to the limit of its rearward movement by engagement with one of the disks so as to open the gates 15, a still further forward movement of the pull rod as it is carried forward by the charging bars, will act to rotate the disk and the shaft 61. The rotation of this shaft 100 through the head 63 and the clutch 64 rotates the sleeve 70 which moves the arms 71 from a vertical position, as in Fig. 8, to a horizontal position, pointing toward the furnace, as shown in Fig. 3. This movement 105 of the arm 71 from a vertical to a horizontal position, through the link 73 operates the rock shaft 51 to throw the clutches to their extreme position, thus connecting the gear 35 with its shaft and disconnecting the gear 34, thus causing the charging bars to travel 110 rearward or out of the furnace. Fig. 3 shows the parts in the position taken as the charging bars 8 are moving rearward, the disk 60^d having released its engagement with 115

120

125

130

the teeth 20^d and the disk 60^a being turned downward for the next dumping operation.

It is particularly to be noted that at the end of each inward travel of the bars, the 5 shaft 61 is turned a quarter of a circle, and that it is necessary to turn this shaft a quarter of a circle in order to throw the clutches 40, 41 from one extreme position to the other.

10 Provision having been made for a return movement of the bars 8, it becomes necessary to provide for a stoppage of the bars after the pocket 12 has been brought beneath the hopper 2. For this purpose, it is necessary 15 of course that the clutches 40 41 be shifted to an intermediate or neutral position so that neither of the gear wheels 34 or 35 is engaged with its shaft 30 or 31. To this end, I provide the bell crank-sleeve 70 with the 20 downwardly extending arm 72 having inwardly projecting from it a pin 80 which extends through an arcuate slot 81 in the side wall 5^a of the casing 5 this slot being indicated by dotted lines in Fig. 3. Formed 25 upon the forward end of one of the bars 8 rearward of the coal pockets is a lug or protuberance 102 having a rounded upper end. This lug or protuberance is of such height that, as shown in Fig. 4, it will engage with 30 the pin 80 as the bars 8 near their rearmost position, and will move this pin and the attached arm 72 rearward, thus depressing the arm 71 and actuating the bell crank 47 through the link 73, the arm 74, the rock 35 shaft 51 and the arm 50.

Referring to the series of views, Figs. 6 to 9, Fig. 6 shows the position of the parts at the time when the bars 8 are in a retracted position and all motion is stopped, the 40 clutches being in their neutral position. It will be seen that the arm 71 is inclined downward and forward, and the arm 72 downward and rearward, while the pin is at the middle of the arcuate slot 81. The 45 clutches being in their intermediate position, it is obvious that the machine will have come to a stop and that it will remain in this inactive position until the clutches are thrown to engage one or the other of the 50 gears 34 or 35 with its respective shaft. Means are provided for manually throwing these clutches, as will be later described, and assuming that one or the other of the 55 clutches is thrown, it will be seen that the throwing of the clutch will cause (through the movement of the bell crank 47, the link 49, the rock shaft 51 and the link 73) a movement of the bell crank 70 which will throw the arm 72 into the position shown in Fig. 7, that is, to the upper extremity of the arcuate slot 81. The bars 8 are now moved forward by the gears, until they reach the position where the load is to be dumped, whereupon the rod 20 will engage 60 the proper disk 60^a, 60^b, 60^c, or 60^d, and the

reversing mechanism will be put into operation, and after dumping, the bars will be returned.

Figs. 3, 4 and 8 show the position of the bell crank 70 at the time when the clutches, 70 having been reversed, the bars 8 are about to move rearwardly, the arm 71 of the bell crank being horizontal, while the arm 72 is vertical, and the pin 80 occupies the forward extremity of the slot 81. As the bar 75 8 moves rearward, the lug 102 engages with the pin 80, as shown in Fig. 9, and moves the pin and the arm 72 rearward to a middle position with regard to the slot 81, that is, the position in Fig. 6, which will thus 80 move the bell crank lever 70 to its middle position and through the link 73, the rock shaft 51 and the bell crank 47, move the shipper arms 44 and 45 to a middle position. The lug 102, after it has raised the 85 pin 80 to a middle position as seen in Fig. 6, passes the pin and continues slightly beyond the same by the force of its momentum, to the position shown in Fig. 6, when the actuating mechanism comes to rest, and 90 the cycle is completed.

It will be seen that when the bell crank 70 is moved to the position shown in Fig. 6 to throw the clutches 40 and 41 to their neutral position, it is necessary to disconnect the bell crank 70 from the shaft 61, for the reason that otherwise the shaft 61 would be reversely moved and the wrong disk 60^a, 60^b, 60^c, or 60^d would be brought with its teeth in position to engage the rod, thus 100 resulting in the next following lot of coal being dumped in the same position as was the previous lot. As a means for disconnecting the clutch-operating levers and rock shafts from the shaft 61, when the pocket-carrying charging bars have returned to their outermost position with the pockets beneath the hopper, I provide the shiftable clutch sleeve 64 which, as before remarked, is normally held by a spring 66 into engagement with the barrel of the bell crank lever 70. This clutch sleeve, however, is laterally shiftable by means of the shipper arms 86 which are pivotally supported in lugs 83 extending from the side wall 5^a of the frame 5. The shipper arms 86 form the vertical arms of a bell crank lever, the other arm of which is designated by the numeral 87, and projects out substantially at right angles to the arms 86. The extremity of this arm 87 is pivotally connected to a link 88, the lower end of which is inwardly bent or offset, as at 89. The lower end of the link 88 is pivotally connected to an arm 90 projecting from a short rock shaft 91. The 110 extremity of the rock shaft carries upon it the upwardly projecting arm 92 carrying a roller 93. The arm 92 projects up beneath the lower flange of the bar 8, and this bar, at its forward end, just rearward of the 115 120 125 130

10 pocket 12 and likewise rearward of the lug 102, is formed with a rib or protuberance 100 which, when the bars 8 are reaching their rearward position, and just prior to the actuation of the arm 72 by the lug 102, acts to depress the arm 92, rotate the rock shaft 91, lift the link 88, and operate the shipper arms 86, thereby shifting the clutch 64 out of engagement with the barrel of 15 the bell crank lever 70, thus disconnecting the bell crank from the shaft 61. As soon as this disconnection has occurred, the lug 102 strikes the pin 80 and operates the bell crank lever 70 to throw the clutches 40 and 20 41 into their neutral position, as before described, but without affecting the shaft 61, so that the ratchet disks on the shaft are left in their previously turned position. As 25 a means for manually operating the rock shaft 51 and throwing the clutches from their neutral position to the position wherein the gears will drive the bars 8 forward into the furnace, I provide the lever 106, the lower end of this lever being pivoted 30 as at 107 to a fixed fulcrum, the intermediate portion of the lever being connected by the link 105 to the arm 108 on the shaft 51. Thus, a movement of the lever 106 will 35 manually shift the clutches.

30 Pivots supported within the stoking hole opening *a* is the door *b* which swings inward to permit the introduction of the bars 8 and the pocket 12, but when said bars and pocket have been withdrawn, swings 40 downward so as to close the opening.

It is necessary of course that the sliding door 4 which closes the lower end of the hopper should be automatically operated when the pocket 12 is carried back to a 45 position beneath the hopper. For this purpose, I provide the door 4 with the rearwardly projecting rack bars 110, and mounted upon a transverse shaft 112 are the pinions 111 which gear with said rack bars 110. The outer extremity of the shaft 112 is provided with a friction wheel 113 which is normally not engaged by the upper face of the outermost bar 8, but is engaged by a raised portion 114 of the bar which is 50 located at the forward extremity of the bar and extends from a point just rearward of the pocket 12, to the end of the bar. When the bar returns to its loading position, the raised face 114 will engage with the 55 friction wheel 113 to rotate the shaft 112, and this through its pinions, will open the gate 104, allowing the coal to fall into the pocket 12, the gate remaining in this position until the bars 8 move into the furnace, 60 when of course the friction wheels 113 will be operated and the gate will be closed. As seen in Fig. 11, the hopper is preferably formed with a contracted throat 120 and with sides that gradually extend downward 65 and outward, as at 121, to the full width

of both of the hoppers 12. While I prefer this form of hopper, as leaving a passageway on either side of the central portion of the hopper, and being therefore particularly convenient for locomotives, yet 70 I do not wish to limit myself to this special form of hopper. It will be seen that one hopper is used for both of the pockets 12, there being two gates 4, however, provided, 75 one for each of the pockets.

It will be of course understood that what I have described relative to one set of pocket-supporting bars 8 and the connections whereby these bars are operated, applies to the opposed set of said bars, and that while 80 I have shown two sets of bars and two pockets with a hopper common to both of the pockets, yet I wish it understood that I might use a greater number of sets of pocket-supporting bars than two, or that I 85 might use only one set of these bars, if found desirable. It will be seen also that each set of these bars is independently operable, that both may be sent into the furnace at one time, or that they may be operated alternately to each other, and that one may be sent into the first position to drop the coal upon the zone *w* of the furnace, or that the other might be moved into the furnace in a position to deposit the coal upon 90 the zone *z*, as may be found most desirable.

I have shown what I believe to be the preferable embodiment of my invention and the preferable details thereof, but I do not wish to be limited to these details nor to the 100 exact arrangement of parts, as it is obvious that this arrangement of details of construction may be changed or varied in many ways, without departing from the principles of my invention.

Having thus described the invention, what I claim is:—

1. A mechanical stoker including a carrier shiftable into and out of a furnace, driving mechanism for operating said carrier, means operatively connected to the driving mechanism for automatically dumping the carrier at a predetermined point, and means for automatically reversing the movement of the driving mechanism when 110 the carrier is dumped to move the carrier out of the furnace.

2. A mechanical stoker including a carrier shiftable into and out of a furnace, driving mechanism for operating said carrier, a detent on the driving mechanism, a member connected to the carrier and engaged by said detent after the carrier is moved forward to a predetermined point to 115 automatically dump the carrier, and mechanism for automatically reversing the movement of the driving mechanism and the carrier after the dumping operation to withdraw the carrier from the furnace.

3. A mechanical stoker including a sup- 120

- port shiftable into and out of a furnace, a fuel carrier on the support, a member extending from the carrier and operatively connected thereto, to dump the carrier when the support has reached a predetermined point within the furnace, reversibly operated gear wheels engaging with the support to move it into or out of the furnace and automatic means for engaging one of said gear wheels with the carrier when the support has reached a predetermined point in its inward movement and the carrier is dumped to return the support and carrier from the furnace.
- 15 4. A mechanical stoker, including a support movable into or out of a furnace, a fuel carrier on the support, gear wheels engaging the support to move it into or out of the furnace, automatic means operatively connected to driving mechanism for reversing the movement of the gear wheels when the carrier has reached a predetermined point where the coal is to be dumped, automatic means for dumping the carrier when said point is reached, and automatic means for stopping the movement of the gear wheel when the carrier has been moved out of the furnace.
- 20 5. A mechanical stoker including a hopper having a gate closing the bottom thereof, a support movable into or out of a furnace, a fuel carrier mounted on the support, means for dumping said carrier once during each forward movement thereof at successive predetermined points within the furnace, gearing operatively engaged with the support for moving it and the carrier into or out of the furnace, a gate closing the discharge mouth of the hopper, and mechanism operatively engaged with the support for opening the gate when the carrier is in alignment therewith.
- 25 6. A mechanical stoker including a shiftable support movable into and out of a furnace, a fuel carrier on said support, means for dumping said fuel carrier, gearing for shifting the support into and out of a furnace, mechanism for reversing or stopping the movement of said gearing, a hopper mounted above the support, a sliding gate closing the discharge mouth of the hopper, and means on the support adjacent to the inner end of the carrier adapted to operatively engage with said gate to open it as the carrier moves into registry with the hopper.
- 30 7. A mechanical stoker including a support movable into or out of a furnace, a fuel carrier mounted on the support, means for dumping the fuel carrier, gearing operatively engaging with the support to shift it into or out of the furnace, means for reversing or stopping the movement of said gearing, a hopper mounted above the support, a sliding gate closing the discharge
- 35 mouth of the hopper and having rack bars, a shaft, pinions engaging with the rack bars of the gate, a gear wheel on the shaft in alignment with said support, and means on the outer end of the support, adjacent to the inner portion of the carrier, engageable with said gear wheel to rotate the shaft and open said gate as the carrier moves into registry therewith.
- 40 8. A mechanical stoker including a support shiftable into or out of a furnace, a fuel carrier on the extremity of the support, a rod operatively connected to dump the carrier, said rod extending rearwardly along the support, and a detent engaging the rod after the support has moved forward to a definite point to pull upon the rod and dump the carrier.
- 45 9. A mechanical stoker including a support shiftable into and out of a furnace, a fuel carrier on the extremity of the support, a rod connected to said carrier and extending rearwardly along the support, and a detent engaging the rod after the support has moved forward to a definite point to pull upon the rod and dump the carrier, said detent being shiftable to engage the rod at any one of a number of predetermined points.
- 50 10. A mechanical stoker including a support shiftable into and out of a furnace, a fuel carrier on the extremity of the support, a rod connected to said carrier and extending rearwardly along the support, and a rotatable detent having a plurality of ratchet teeth projecting in different directions and on different transverse planes, said teeth adapted to successively engage said rod at predetermined points in its length to arrest the motion of the rod and dump said carrier.
- 55 11. A mechanical stoker including a support shiftable into and out of a furnace, a fuel carrier on the extremity of the support, a rod connected to said carrier and extending rearwardly along the support, and a rotatable detent comprising a plurality of ratchet wheels having teeth projecting in different directions, adapted to successively engage said rod at a plurality of predetermined points in its length to arrest the motion of said rod and dump said carrier.
- 60 12. A mechanical stoker including a support movable into and out of a furnace, a fuel carrier on the extremity of the support, a rod connected to said fuel carrier to dump the same, and extending rearwardly along the support, said rod having thereon a plurality of differently placed stops, and a detent shiftable to engage with one or another of said stops, whereby the rod may be arrested in its forward movement at any one of a number of predetermined points to operate the dumping mechanism.
- 65 13. A mechanical stoker including a support shiftable into or out of a furnace, a fuel carrier on the extremity of said sup-

port, an operating rod connected to the fuel carrier to dump the same, and extending rearwardly along the support, said operating rod having thereon a plurality of differentially placed projecting stops, and a detent comprising a plurality of members shiftable to bring one or another into position to engage the corresponding stop on said rod to arrest the movement of said rod upon the forward movement of the support and operate said dumping rod.

14. A mechanical stoker including a support movable into or out of a furnace, a fuel carrier carried on the support, gearing engaging with the support and adapted to shift it, a hopper having a discharge mouth with which the carrier is adapted to register when withdrawn from the furnace, a dumping rod attached to and extending rearward from the carrier, and means for operating said dumping rod, consisting of a plurality of members having teeth extending in different directions, each member being in a different plane from the other member, and said rod being provided with a plurality of differently placed stops with which the corresponding detent member is adapted to engage to arrest the movement of the rod and dump the carrier.

15. The combination with a furnace having a stoking opening therein, of a stoker having a support movable into the furnace through said stoking opening, a fuel carrier carried upon the extremity of the support, gear wheels engaging with said support to shift it into or out of the furnace, driving mechanism connected to said gear wheels, means for reversing or stopping the movement of the gear wheels, an operating rod connected to the carrier, said rod having a plurality of stops placed at different distances along the rod and also placed in different lateral planes, and a detent having a plurality of teeth projecting in different directions and located in different lateral planes, said teeth corresponding with the stops on said carrier-operating rod, and yielding means for holding the said detent member from rotation until said carrier has been dumped, and afterward permitting the rotation of the detent member to bring another tooth into position to engage another stop upon said operating bar.

16. In a mechanical stoker, the combination with a furnace having a stoking opening, of a pair of spaced parallel supporting bars, said bars being toothed, rollers upon which said bars are supported, gear wheels engaging with the bars to shift them into or out of the furnace, driving mechanism for said gear wheels, a hopper mounted above the bars and exterior to the furnace, said hopper being located in a plane between the bars, a coal carrier carried upon the extremity of the bars, gates closing the bottom

of the coal carrier, an operating rod connected with the gates, and means exterior to the furnace for moving the operating rod to open the gates.

17. The combination with a longitudinally movable support, of oppositely movable driven elements engaged with said support, a driving element, clutch mechanism operatively engaging one or the other of the driven elements with the driving element, a shiftable element having a detent thereon, a stop on the said longitudinally movable support engaging with the detent to rotate the detent-carrying element when the supporting bar has reached the limit of its travel in one direction, and a connection between said shiftable detent-carrying element and the clutch mechanism, whereby the latter is operated upon an operation of the former.

18. The combination with a movable supporting bar, of oppositely movable driven elements engaging with said bar, a driving element, clutch mechanism for operatively engaging one or the other of said driven elements with the driving element, a rock shaft, a detent on the shaft, a stop carried by the movable bar, engaging with the detent to move it and rotate said rock shaft when the supporting bar has reached the limit of its travel in one direction, a connection between said rock shaft and the clutch mechanism, whereby the latter is operated upon a rotation of the former to reverse the motion of the supporting bar, an arm on the said rock shaft, whereby it may be rocked, and a projection on the forward end of the supporting bar, engageable with the said arm to move the rock shaft to a neutral position and throw the clutches into a neutral position out of engagement with either of the driven elements.

19. The combination with a longitudinally movable supporting bar, of oppositely movable driven elements engaging with said bar, a driving element, clutch mechanism for operatively engaging one or the other of the driven elements with the driving element, a rock shaft, a rotatable detent element carried on the shaft and having a projecting tooth whereby it may be turned to turn the rock shaft, a stop on the movable bar engaging with the tooth on the detent to move it and rotate said rock shaft, said stop being so located that it will engage with said tooth when the supporting bar has reached the limit of its movement in one direction, a connection between said rock shaft and the clutch mechanism, whereby the clutch mechanism is operated upon a movement of the rock shaft in either direction, an arm on the said shaft, and a projection on the forward end of the supporting bar, engaging with said arm when the supporting bar has reached the outward limit of its movement to move said arm to a neutral position and

thereby shift the clutches to a neutral position.

20. The combination with a movable bar, of oppositely movable driven elements engaging with said bar, a driving element, clutch mechanism for driving one or the other of said driven elements with the driving element, a rock shaft, a rotatable detent element on the rock shaft having a projecting tooth, a stop on the movable bar engaging with the tooth to move the detent and rotate said rock shaft, said stop being so located as to engage with the detent when the movable bar has reached the limit of its movement in one direction, a connection between said rock shaft and the clutch mechanism, whereby a rotative movement of the rock shaft in one direction or the other will cause the clutch mechanism to engage one or the other of the driven gears with the driving element, an arm on the rock shaft whereby it may be rocked, a projection on the supporting bar, engageable with said arm, a manually operating lever, and connections between said operating lever and said clutches.

21. The combination with a longitudinally movable supporting bar, of oppositely movable driven elements engaging with said bar to move the same in one direction or the other, a driving element, clutch mechanism for operatively engaging one or the other of the driven elements with the driving element, a rock shaft, detent mechanism on the shaft, comprising a plurality of differently directed teeth, said teeth being located in different transverse planes, a series of stops on the movable bar, said stops being located in planes corresponding with the planes of the respective detent teeth and acting to move said detent teeth and rotate the rock shaft when the supporting bar has moved in one direction to any predetermined position, a bell crank loosely mounted on the rock shaft, a connection between said bell crank and the clutch mechanism, a clutch which, when moved in one position engages the bell crank with the said rock shaft, an arm on the rock shaft whereby it may be rocked, a projection on the movable supporting bar, engageable with said arm to rock the shaft and bell crank to a neutral position, and thereby throw the clutch mechanism to a neutral position, said stop being so located as to engage said arm when the supporting bar has reached the limit of its movement in an opposite direction to the movement of the first referred to, and mechanism operated by the arrival of said supporting bar at its last named position, whereby the clutch between the bell crank and the rock shaft will be disengaged.

22. A mechanical stoker including a supporting bar carrying a fuel pocket at one end, said supporting bar having rack teeth

thereon, parallel shafts having pinions engaging with said rack teeth, driven gears loose on said shafts and engaging with each other, a driving gear engageable with one of said driven gears, opposed clutch mechanism for engaging either of said driven gears with its respective shaft, a rock shaft having a manually operated lever and connected to said clutch mechanism, a rock shaft having thereon a rotatable detent mechanism formed with a number of differently projecting teeth, said teeth being located in vertical planes, a shaft upon which said detent mechanism is mounted, a bell crank lever loosely mounted upon said shaft and having a connection from one of its arms to the said rock shaft, whereby a movement of the bell crank lever shall operate the rock shaft to throw the clutches from one full position to the other, a spring clutch on said shaft engaging the bell crank lever with the shaft, a series of stops on the supporting bar engaging with said series of detent teeth to rotate the shaft through an arc of a circle and thereby turn the rock shaft and shift the clutches, said stop being located so as to engage the detent when the supporting bar has reached the limit of its movement in one direction, a stop on the supporting bar so located as to engage with one arm of the bell crank lever upon the arrival of the supporting bar at the limit of its movement in the other direction and to move said bell crank lever to a neutral position, to throw the clutches entirely out of engagement with the driven gears, a shipper lever connected to the clutch mechanism which engages the bell crank lever with its shaft, a rock shaft connected to said clutch, shipper mechanism to operate the support and having an upwardly projecting arm, and a projection on said supporting bar, engageable to depress said arm and operate the shipper to disconnect the clutch from the bell crank lever when the supporting bar has reached the limit of its inward movement.

23. A mechanical stoker including a fuel carrier; means for reciprocating the carrier and thereby moving it into a furnace and retracting it therefrom by the same path, an automatic means for dumping the carrier, once for each movement thereof, over separate and successive portions of a grate surface.

24. A mechanical stoker, including a fuel carrier, shiftable into and out of a furnace by the same path and movable successively to different predetermined points in the furnace upon each inward movement of the carrier into the furnace, and automatic means for dumping the carrier when the carrier has reached such predetermined point.

25. A mechanical stoker, including a fuel carrier, shiftable into and out of a furnace,

the carrier being movable upon each inward movement successively to different predetermined points in the furnace, and means for automatically dumping the carrier at the limit of each of its inward movements.

26. A mechanical stoker including a support shiftable into and out of a furnace and movable successively to different predetermined points in the furnace, automatic means for dumping the carrier when the carrier has reached its predetermined position, and automatic means for retracting said support to move the carrier out of the furnace after the carrier has been dumped.

27. In a mechanical stoker, the combination with a furnace having a stoking opening, of a pair of spaced parallel supporting bars, said bars being toothed, rollers upon which the bars are supported, gear wheels engaging the bars to shift them into or out of a furnace, driving mechanism for the

gear wheels, a hopper mounted above the bars and exterior to the furnace, a carrier mounted upon the extremity of the bars, an operating rod connected with the carrier, 25 means operatively connected to the driving mechanism for engaging said operating rod to dump the carrier at successive predetermined points within the furnace, means exterior to the furnace for moving the operating rod to dump the carrier, automatic means for reversing the movement of said gear wheels to retract the supporting bars after the carrier has been dumped, and manually operated means for reversing the 35 movement of said gear wheels.

In testimony whereof I affix my signature in presence of two witnesses.

CHARLES HARTER. [L. S.]
